COIN OPERATED MACHINE

William G. Peters, Chicago, Ill., assignor to
Richard Groetchen, Chicago, Ill.

Application January 13, 1936, Serial No. 58,910

11 Claims. (Cl. 273—143)

This invention relates to a coin operated mechanism, in which the mechanism may be coin controlled and in which the mechanism is arranged to operate a slide or carriage to permit movement of the carriage to a greater or less degree and thereby to control the movement of any mechanism operated by or in response to the movement of the carriage.

One object of the invention is, therefore, to provide a mechanism in which the movement of the carriage is controlled by the movement of certain controlling parts within the mechanism. Another object of the invention is to provide controlling parts and means for operating them, in which the operation of the controlling parts is as silent as possible and in which it is as accurate and certain of movement as possible.

Another object is to provide in such a device a series of display parts and means for operating them, to control the movement of a carriage or analogous mechanism and thereby to control the movement of a mechanism operated by the carriage. A further object is to provide a reel operating and positioning mechanism.

Other objects will appear from time to time in the specification and claims.

The invention is illustrated more or less diagrammatically in the accompany drawings, wherein:

Figure 1 is a side elevation of the mechanism, with parts in section, taken inside the casing;

Figure 2 is a fragmentary top plan view;

Figure 3 is a longitudinal vertical section taken at line 3—3 of Figure 1;

Figure 4 is a transverse vertical section taken at line 4—4 of Figure 3;

Figure 5 is a transverse vertical section taken at line 5—5 of Figure 3;

Figure 6 is a rear view of the lower part of the mechanism, with parts in section and parts broken away;

Figure 7 is a transverse vertical section taken at line 7—7 of Figure 3;

Figure 8 is a longitudinal vertical section, taken at line 8—8 of Figure 2, showing the mechanism of that figure, with parts in elevation and parts in section;

Figure 9 is a partial side elevation with parts in section showing some of the parts of Fig. 1 in different positions;

Figure 10 is a view similar to Fig. 9, illustrating the parts in yet another position; and

Figure 11 is a longitudinal section taken at line 11—11 of Figure 9.

Like parts are designated by like characters throughout the specification and drawings.

The machine may be provided with any suitable base. As shown it has a base plate 1 which is provided with suitable points for attachment of the parts of the mechanism. These need not be numbered nor described in detail. Formed preferably integrally with the base plate 1 are supports 2 and 3. To the support 2 is preferably removably fastened a plate member 4 which serves to support various parts of the mechanism. A generally similar plate 5 is preferably removably attached to the support 3.

6 is a main shaft supported at one end in the plate 4 and carrying at its outer end a positioning collar 7. At its other end, beyond the plate 5, the shaft 6 is mounted within a sleeve 8 which may be secured to the shaft by a pin 9. The shaft is supported preferably adjacent one end of the sleeve 8 in the plate 5, in any bearing formed in or supported by the plate. The sleeve 8 carries a handle 10 and may also carry a flange 11 which serves to close the perforation 12 formed in a casing or housing member 13. The handle may be secured to the flange 11 by screws 14 or may be made integrally with it or otherwise, if desired. The sleeve 8 carries a double stop or limit member 15, 16. Positioned in line with the stop member, on a suitable support 17, is an abutment provided with limiting faces 18, 19 to contact, respectively, the stop members 15 and 16 and to limit movement of the operation handle 10 and consequently of the shaft 6. Formed also on the sleeve is a lug 20 the purpose of which will be described below.

Positioned in the plate 4 above the shaft 6 is a threaded bearing plug 21, provided with a hollow bearing portion 22 and held in place by a lock nut 23. One end of a shaft 24 is supported within the bearing portion 22. The opposite end of the shaft is supported within a bearing portion 25 in a bearing support 26 which is threaded into the plate 5 above the shaft 6 and is locked in place by a lock nut 27. The bearing support 26 is provided on its exterior with a relatively elongated smooth bearing surface 28. An indicating reel 29, which may carry a strip 30 provided with suitable indicia, is provided with a hub or other central member 31 which is positioned upon the shaft 24 and may be pinned to it by a pin 32 or otherwise held in fixed position upon the shaft.

Adjacent the opposite end of the shaft 24 a star wheel 33 is secured to the shaft. It may be pressed in position, pinned or otherwise held against movement with respect to the shaft.

5 Mounted loosely on the shaft, between the reel 29 and the star wheel 33, is a sleeve 34. Fixed upon this sleeve is a second reel 35, similar in construction to the reel 29 and fixed on the sleeve 34 adjacent its opposite end is a second star wheel 36.

10 Loosely mounted on the sleeve 34 is a second sleeve 37 which has fixed upon it a third reel 38 generally similar to the reels 29 and 35, and fixed also upon the sleeve 37 is a third star wheel 39. The reels may be formed with spokes, as shown, or with webs or of any other construction so long as they do not interfere with the operation of the other parts of the mechanism.

15 The star wheel 33 is provided with a plurality of points 40. In the form shown they are ten in number but any number could be used. Generally opposite each point 40 the star wheel is provided with perforations 41 which are positioned, in the form of the invention shown here, at various 20 distances from the center of the wheel. The star wheel may also carry one or more outwardly projecting pins 42 which may be of generally varying lengths, as shown particularly in Figure 3. One or more of the perforations 41 may be 25 provided in its rear with a boss 43 perforated as at 44 to receive a pin so that the passage through the hole may, if desired, be prevented.

30 Positioned as a part of, and preferably formed integrally with the star wheel 33 is a generally conical cam member 45. In the form shown this cam member has five concave cam portions 46 which are preferably equal in size to each other and equally distributed about the diameter of the cam. The cam member 45 is so positioned 35 that one of the holes 41 lies opposite the base of each of the cam portions 46. Positioned between the cam portions 46 are raised cam portions 47 so positioned that one of the holes 41 lies opposite the base of each such raised cam portion 40 47. It will be noticed that the cam portions 46 are not all of the same inclination. This is due to the fact that the holes 41 are not all spaced at the same distance from the center of the star wheel and the angle of inclination of the various 45 cam portions 46 is such that the cam terminates at its lower edge at the periphery of one of the holes.

50 The second star wheel 36, which is shown in detail in Figure 5, is the same in outline as the one 33 just described. It is provided with points 48 and perforations 49. The perforations are given generally the same spacing on the star wheel as that given to the perforations 41 on the wheel 33, although this is not an absolutely 55 essential relationship.

50 The third star wheel 39 which is shown in detail in Figure 7, is generally the same in outline and shape as the first and second star wheels. It is provided with a similar number of points 60 50 with perforations or holes 51. The perforations 51 are not the same, either in number or position, as the perforations 41 and 49 in the first and second star wheels, respectively. In addition to the holes 51 the star wheel 39 has 65 a plurality of depressions 52 formed in the wheel itself and closed as at 53. In addition to the holes and the depressions the star wheel 39 is provided with a slot 54 and it is thickened as at 55. This thickened portion serves as a stop in 70 a manner which will be described below.

75 The means for rotating the reels and associated parts will now be described. The rotation of the reels is initiated by rotating the handle 10, which rotates the shaft 6 in the direction of 75 the arrow in Figure 1. This movement carries

the sleeve 8, and the lug 20 fixed on it, engages the pin 56 fixed on a disc 57, which is itself loose on the shaft 6. The disc 57 is normally held against movement and in a position in which the pin 56 engages the lug 20 by means of a 5 spring 58. The disc 57 is provided with a depression 59, a series of teeth 60, a second depression 61 and a third depression 62, which latter may be deeper than the depression 61 and shaped to provide a shoulder. Intermediate the 10 depressions 61, 62 is formed a kick-off point 62a. In the initial rotation of the disc 57, a pawl 63, which is pivoted at 64 and provided with a spring 65, is rotated by the depression 59 and moved into engagement with the teeth 60. This is indicated in the dotted line position of Figure 1. As the rotation of the disc proceeds, the pin 66 positioned on an arm 67, rides from the depression 61 to the depression 62 and as the rotation continues further, the arm 67 is carried 20 by the disc to the left as shown in Figure 1. The pin 66, in addition to contacting the depressions in the disc 57, extends through the arm to project as at 66a for engagement with a notch 68 in a flange 69 in a sleeve 70 positioned for rotation on the shaft 6.

25 The rotation of the shaft 6 and of the sleeve 70 causes the rotation of the reels and of the star wheels and this rotation will now be described. At its upper end the arm 67 is pivoted 30 on a lever arm 71 which is normally held in a downward position by a spring 72. The lever arm is provided with a hub 73 positioned upon the bearing member 26. At its lower end the lever arm is provided with a lateral extension 35 74. The extension 74 is provided with a generally upwardly extending lug 75 and a generally laterally extending lug 76. Projecting from the extension 74 is a pin 77 upon which is pivoted a kick-off plate 78, having on one side a normally 40 downwardly extending flange 79 and on the opposite side a shorter, downwardly extending flange 80 which is wider than the member 79 and extends the whole length of the plate 78. As rotation continues the parts finally reach the 45 extreme dotted line position of Figure 5. In that position the flange 79 of the plate 78 is contacted by the spring cam 81 which is mounted at 82 and the plate is rotated into engagement with the star wheel.

50 During the rotation of the disc 57 and movement of the arm 67 and associated parts, which has just been described, the pin 66a which is in reality a continuation of the pin 66, moves with it and actuates the following mechanisms:

55 This pin, lying in the slot 68, formed in the flange 69, which is normally held against movement by a spring 83, has a limited play within the slot 68 and as the movement of the disc 57 continues so that the pin 66 is engaged in 60 the depression 62, the pin 66a moves in the depression 68, strikes its end, and continues to move, carrying with it the flange 69 on the sleeve 70. As the rotation continues the lower face of the lever 67 engages the face of the cam 84 65 and finally the lower end of the lever 67 is moved so that the pin 66 is lifted free of the depression 62. At the same time the pin 66a is lifted out of the depression 68, and the spring 72 is then free to pull down the arm 71 to the 70 starting position and to actuate the kick-off mechanism as follows: The plate 78, lying at that time in the dotted line position of Figure 5, is in position to strike one of the faces between the points of the star wheels and thus to spin 75

the three star wheels in its downward movement. Since each star wheel is connected to a reel, as above mentioned, the actuation of the star wheels actuates the reels.

5 The star wheels are normally held against spinning or other movement and in order to permit the spinning movement described above, it is necessary to free them from this checking action. This is done during the rotation of the disc 57 5 as described above. A checking and aligning mechanism is provided for each of the star wheels. In the form of the invention shown herewith there is provided a lever 85 for each wheel. The levers are pivoted at 86 and carry at their upper 10 ends rollers 87 of such size as to fit between the points of the star wheels. A perforated lug 88 is formed on each of the levers 85 to receive a spring 89 secured at any suitable point. The springs, when free to do so, hold the rollers in contact with the star wheels. At their lower ends each of the levers 85 carries a curved projection 90. On the sleeve 70 is formed a projection 91 which carries a curved cam plate 92. During the 15 rotation above described the cam is moved from the full line position of Figure 5 to the dotted line position of that figure, contacting the curved portions 90 and moving the levers and rollers out of contact with the star wheels into the dotted line position of Figure 5.

20 30 When the pins 66 and 66a have been freed for return movement, the spring 83 commences to return the assembly to the full line position of Figure 5. This movement is retarded, however, by a governor indicated generally at 93. The 35 governor may be of any suitable design, mechanical, hydraulic, or otherwise, and slows down return of the parts under the influence of spring 83. In the form shown, the governor comprises a fan 94 operated by gearing, not shown, as its 40 details form no essential part of the present invention. The governor operating means comprises a link 95 fastened to the extension 96 which is formed with or attached to the flange 69 and which is attached at its opposite end to a crank 45 arm 97. The extension 96 also engages a stop 98 to limit return movement of the parts under the influence of the spring 83.

During the movement above described, the pawl 63 has been moved from the full line position of 50 Figure 1 to the dotted line position of that figure, and as the rotation of the disc 57 is continued, the pawl has been riding over the teeth. As rotation is stopped, the pawl will engage the teeth and prevent reverse movement. It is necessary 55 finally to move the pawl 63 so that when the desired reverse movement just above described is to occur, the pawl will not lock the handle against return movement. The pawl, of course, does not lock the inner movement after the pins 66 and 66a have been raised by the cam 84. The 60 unlocking of the pawl is effected as follows: After the pawl has ridden over the last of the teeth 60 it drops into the depression 61 and the spring 65 moves it to the neutral position and there- 65 after in the reverse of the disc 57 the round face of the pawl 63 rides over the teeth and does not engage or lock them.

A controlled brake means is provided for each 70 of the reels. This braking means, in the form shown, includes a support 99. Pivoted on the support 99 are three spring brake arms 100, 101 and 102. They are arranged respectively to engage the rim of the reels 29, 35 and 38 and each is provided with an adjustable contact member 75 103, 104 and 105, which are mounted, respectively,

in the brakes 100, 101 and 102. Each of the spring arms carries a wiper 106 which is of suitable size and material to cause the desired friction on the rim of the reel with which it is in contact. As a means for actuating the brakes to stop the reels, the sleeve 70 is provided with an extension 107 to which a brake actuating arm 108, carrying a laterally bent portion 109 is secured. When the handle is actuated to move the shaft 6 the brake actuating member 108, 109 moves in the direction of the arrow in Figure 7. In its movement it contacts successively and in the order mentioned the contact members 105, 104, 103. The reels are at this time, however, stationary and the member 109 is moved sufficiently so that it finally clears the contact member 103 and none of the brakes is at that time pressed against the reel sufficiently to stop it or prevent its movement, so that when the kick-off movement occurs, all of the reels start. With the 20 reverse movement of the shaft 6 and sleeve 70 the braking member 108, 109 moves clockwise as shown in Figure 7, and first contacts the contact member 103 of the brake 100 which is in contact with the reel 29 and increases the pressure and friction sufficiently to stop it. It contacts the other contact members successively in its return movement and so stops the reels and the star wheels which are attached, as above explained, one to each reel. After the star wheels are 30 stopped the rollers 87 drop into the spaces between the points of the star wheels and accurately align the parts.

A carriage is associated with the mechanism and the movement of the carriage is controlled 35 by the mechanism. The carriage may be used to accomplish many different purposes and to actuate a variety of mechanisms and the exact details of the mechanism operated by the carriage are not illustrated herewith and form no essential 40 part of the present invention; the carriage may actuate a vending mechanism, may actuate a change-making mechanism or means for delivering articles, or it may actuate any desired mechanism. In the form shown, a laterally extending 45 cross member 110, having downwardly depending portions 111 and 112, which are attached respectively to the plates 4 and 5, is provided. A pair of ears 113 is formed preferably integrally with the member 110 to which is secured a carriage 50 support 114. This support is shown as round in the present form of the invention but might be of any desired shape. It is provided with a keyway 115 within which a key 116 on a carriage 117 is positioned. The carriage is of suitable shape to 55 fit upon or to embrace the guide 114. It is normally held against movement by a spring 118 which is fastened on a stud 119 which is itself attached to or formed as a part of one of the ears 113. At its opposite end the spring is fastened 60 to a stud 120 formed as a part of or attached to the carriage 117. The spring normally tends to move the carriage to the left from the position shown for example in Figures 2 and 8. Formed 65 on the carriage 117 are a pair of lugs 121 to which is attached a U-shaped aligning member 122, one portion of which, 123, is set at an angle with respect to the remainder. The outer or free end of the portion 123 is beveled or inclined as at 124. 70 Pivoted between the lugs 121 on a pin 125 is an arm 126 which carries a preferably rounded pin 127 of such size and shape that it can pass through the perforations in the star wheels when the parts are aligned to permit it to do so. De- 75

pending downwardly from the carriage 117 is a lug 128 carrying a headed pin 129.

The pin 129 is arranged to engage the upper end of a lever 130 which is pivoted as at 131 on a support 132 fixed to the base 1. At its lower end the lever 130 is provided with a concave socket 130a to receive the rounded end 133 of a toggle 134. At its opposite end the toggle 134 is provided with a rounded portion 135 fitting within a concave depression 136 formed in an arm 137 which is attached to or formed as a part of the sleeve 70. Thus when the sleeve is rotated the lever 130 is moved from the position of Figure 3 to the right to move the carriage to the right in the direction of the arrow against the resistance of the spring 118.

The reverse movement of the carriage occurs after the kick-off and its extent is determined by the position which the star wheels assume. In one position the pin 127 can penetrate only through the first star wheel and in other positions it may penetrate through the second to reach the third or may penetrate entirely through the third. When that occurs the final limit of the return movement of the carriage is determined by the contact of one or another of the stop pins 42 with the bracket 126 of the carriage at a point which, in the present form of the invention, is just above the pin 127.

The operation of the device has been largely described in connection with the detailed description of the parts above set out. In general the parts are stationary. When the handle is operated, the following movements take place: The carriage is moved to the right, the reel actuating mechanism is rotated and the reels, with their associated star wheels, are rotated by the kick-off movement. The reels are then successively stopped by the brakes and are further aligned by the rollers which fit between the points of the star wheels. When this has occurred reverse or return movement of the carriage takes place. In the particular form of the invention shown herewith, however, the rollers are not finally dropped into aligning position between the points of the star wheels until the carriage has started its return movement, but before the pin 127 of the carriage has penetrated the first star wheel.

With the reels and star wheels stopped in position by the brakes and held and aligned by the rollers, the return movement of the carriage continues. During the first part of its return movement the carriage and the lever 130 move together, the governor mechanism serving to slow down the return movement of the sleeve 70 with which the lever 130 is connected, and thus slowing down the movement of the lever and the carriage which is still in contact with it.

The pin 127 which is pivoted on the carriage and, therefore, free for some movement, contacts first some part of the cam portion of the conical part of the star wheel 33 and the point of this pin may ride down either the hollow of one of the concave cam portions 46 or the crest of one of the intervening cam portions 47. In either event it will fall into and penetrate through one of the perforations 41. One or more of the perforations 41 may be stopped by a pin 44 and in that event, should the pin 127 strike one of the stop pins 44, it will not penetrate further and the movement of the carriage is terminated. However, if the pin strikes one of the holes that is not blocked by a stop pin 44, it penetrates and comes in contact with the second star wheel 36. Further movement of the carriage depends upon the

positions assumed by the second and third star wheels 36 and 39. They may have assumed such a position that the pin can penetrate through the second but not through the third or they may have assumed a position in which the pin can penetrate all three. If that is the case, the carriage is finally stopped in its return movement by contact of one of the outwardly projecting stop pins 42 in the star wheel 33, with the bracket 126 of the carriage or with some other part of the carriage. Thus depending upon the positions which the reels and star wheels have assumed, the return movement of the carriage is controlled and the exact degree of this movement may be almost infinitely varied. When the carriage is finally stopped the lever 130 continues to move until it returns to its original position.

While it rarely occurs, there is a chance that one or more of the star wheels might stop so that a roller would be centered on one of its points. The member 122 supported from the carriage acts as a cam and should the star wheel stop on center, this member, during the initial movement of the carriage, will contact a point of the star wheel and move it off center. The reel 38 in the form shown, is provided with spokes so positioned that they will not stop the member 122, which may pass between them in case the position which the star wheels assume is such as to allow the carriage sufficient return movement to carry the member 122 through the reel.

While the mechanism has been described as being controlled by some form of coin receiving assembly, it is not limited to such a use. The purpose of the mechanism illustrated in detail in Figures 9 and 10 and described in the paragraphs just below, is to prevent improper or unauthorized operation of the device. It might be to prevent its operation without the insertion of coins or to prevent its operation at the wrong time in its total cycle, and hence the movement of the shaft 146 and the link 144 and the cam lever 140 might be prevented or permitted in response to any operation in the total cycle. If the device shown here is associated with another mechanism, whatever its nature, the connection between that mechanism and the shaft 146 and associated parts may be such as to prevent improper or unauthorized operation of the device by the movement and through the use of the parts just described above.

In order to render the star wheel and reel actuating mechanism above described ineffective, when the handle 10 is manipulated improperly or with intention to cheat, I have illustrated the following mechanism:

Referring particularly to Figures 1, 5, 9, 10 and 11, a cam lever 140, pivoted as at 141 and formed with a nose or camming lug 142 is positioned adjacent the disc 57. Pivoted to the free end of the cam lever 140 as at 143 is a connecting link 144 having its opposite end pivoted to a lever 145. The lever 145 may, for example, by means of a shaft 146, be connected with any suitable coin receiving mechanism, not illustrated, which prevents counterclockwise rotation of the shaft 146 of the parts as illustrated in Figure 1; but which, if a coin has been inserted, will permit such rotation.

The cam lever 140 is normally thrust against the periphery 148 of the disc 57 by means of a spring 147, anchored at one end to the connecting link 144 and having its other end secured either to the plate 5 or to the lever 145. The disc 57 is formed with a camming portion 149 of a smaller radius to permit counterclockwise rota-

tion of the cam lever 140, referring to Figures 1, 9 and 10, which by means of the above described linkage rotates the shaft 146 in the direction of the arrow of Figure 1, when free to do so.

Secured to the connecting link 144 is a generally U-shaped lifting bar 150 which straddles the plate 5. It has one elongated end 151 projecting beneath and in alignment with the link 67, if said link is in inoperative position.

Assuming that the operator rotates the handle 10 without first depositing a coin, the following action takes place: In the starting or initial position, illustrated in Figure 1, the nose 142 of the cam lever 140 is in engagement with the periphery 148 of the disc 57. As the disc is rotated in the direction of the arrow by means of the lug 20 and co-operating pin 56, the nose 142 drops into the cut away cam portion 149, illustrated in Figure 10 and thus lifts the connecting link 144 and the lifting bar 150 which in turn by means of its elongated end 151 lifts the link 67 sufficiently so as to withdraw the pin 66 of said link from the depression 62 of the disc 57. Further rotation of the handle 10 merely rotates the disc 57 without actuating either the reel spinning or the carriage actuating mechanism.

However, if the operator has first deposited a coin in the coin receiving mechanism above referred to, to thus prevent rotation of the shaft 146, the cam lever 140 and connecting link 144 remain immovable and thus ineffective, and the normal operation of the various mechanisms takes place.

It has been found desirable to prevent the pin 66 of the link 67, after having completed its kick-off function, from dropping by gravity into the depression 62, 61 at the return movement of the rotating disc 57. As previously described, on the return movement of the disc 57, the pawl 63 rides over the teeth 60 as illustrated in Figure 9.

Mounted for rotation upon the pivot pin 64 independently of rotation of the pawl 63 is a lifting lever 152 having a curved end portion 153 which is normally supported upon the pin 56 as shown in Figures 1 and 10. Fixed to the lifting lever 152 is a pin 154 projecting into the path of the pawl 63, as shown in Figure 11. When the disc 57 is rotated in the direction of the arrows of Figures 1 and 10 the lifting lever 152 rests upon the pin 56 and substantially no movement of this lever takes place. However, at or near the end of rotation in such direction, the pawl 63 clears the teeth 60 and is free to be rotated by means of its coacting spring 65 within the depression 59 of the disc 57. As soon as return movement of the disc commences, the pawl 63 is rotated counterclockwise, referring to Figure 9, comes into contact with the pin 154 and rotates the lifting lever 152 which in turn engages the pin 66 and thus lifts the free end of the link 67 to the position illustrated in Figure 9.

At or about at the end of return movement, or the initial position of the disc 57, the pawl 63 is permitted to rotate back to its initial position within the depression 59 and the lifting link drops upon the pin 56. The free end of the link 67 follows the lifting lever until the pin 66 comes at rest in the depression 61 of the disc 57. It will thus be seen that the actuating link 67 is rendered ineffective until the disc 57 has assumed its initial position.

It will be understood, of course, that the coin previously deposited has during the cycle of operation been moved in any suitable manner so as to unlock the mechanism for locking the shaft

146 and another coin is required before the machine can again be successfully operated.

The kick-off point 62a serves to throw the pin 66 and associated link 67 upwardly and above the periphery of the disc 57, should the operator attempt to jerk the operating handle 10 in order to play without first depositing a coin or token, relying on the time consumed for the spring 147 to act upon the link and associated lifting bar 151.

There is thus provided this lost play connection which further safeguards the machine and further prevents its unauthorized or incorrect use.

I claim:

1. In combination in a machine including a plurality of wheels positioned side by side, a movable mounted carriage, means for setting said wheels in motion simultaneously and for stopping them successively, means for moving said carriage, means for returning said carriage, a member carried by said carriage adapted to contact said wheels, the return movement of said carriage being determined by the position assumed by said wheels upon being stopped, said wheels being perforated, the said member carried by said carriage adapted to penetrate one or more of said wheels when the perforations of said wheels are in line with said member.

2. In combination in a machine including a plurality of reels positioned side by side, a movable mounted carriage, means for setting said reels in motion simultaneously and for stopping them successively, means for moving said carriage, a plurality of positioning wheels, means for returning said carriage, a member carried by said carriage adapted to contact said positioning wheels, the return movement of said carriage being determined by the position assumed by said wheels upon being stopped, said wheels being perforated, the said member carried by said carriage adapted to penetrate one or more of said wheels when the perforations of said wheels are in line with said member.

3. In combination in a machine including a plurality of reels positioned side by side, a movable mounted carriage, means for setting said reels in motion simultaneously and for stopping them successively, means for moving said carriage, a plurality of differently shaped positioning wheels associated one with each of said reels, means for returning said carriage, a member carried by said carriage adapted to contact said positioning wheels, and to extend beyond one or more of them, the return movement of said carriage being determined by the position assumed by said wheels when stopped.

4. In combination in a machine including a plurality of reels positioned side by side, a movable mounted carriage, means for setting said reels in motion simultaneously and for stopping them successively, means for moving said carriage, a plurality of positioning wheels associated one with each of said reels, means for returning said carriage, a member carried by said carriage adapted to contact said positioning wheels, the return movement of said carriage being determined by the position assumed by said wheels upon being stopped, said wheels being perforated, the said member carried by said carriage adapted to penetrate one or more of said wheels when the perforations of said wheels are in line with said member.

5. In combination in a machine including a plurality of reels positioned side by side, a movable mounted carriage, means for setting said

- reels in motion simultaneously and for stopping them successively, means for moving said carriage, a plurality of positioning wheels, means for returning said carriage, a member carried by said carriage adapted to contact said positioning wheels upon being stopped, perforations formed in said wheels, said member adapted to extend through the perforation of a wheel when the latter is stopped in line with said member, the return movement of said carriage being determined by the position assumed by said wheels upon being stopped.
6. In combination in a machine including a plurality of reels positioned side by side, a movable mounted carriage, means for setting said reels in motion simultaneously and for stopping them successively, means for moving said carriage, a plurality of positioning wheels associated one with each of said reels, means for returning said carriage, a member carried by said carriage adapted to contact said positioning wheels, perforations and guiding cams formed in said wheels adapted to guide said contact member, said member adapted to extend through the perforation of a wheel when the latter is stopped in line with said member, the return movement of said carriage being determined by the position assumed by said wheels upon being stopped.
7. In combination in a machine having a plurality of reels, means for rotating said reels, comprising a plurality of star wheels associated one with each reel, and a unitary member for rotating said star wheels, said member comprising a lever arm, concentric with said star wheels, a link attached to said lever arm, means for moving said link to move said lever arm, a star wheel contacting member on said lever arm, means for positioning it when the star wheel contacting member is in striking position, and means for releasing said link to free the lever arm for return movement and spring means for returning said lever arm to actuate said star wheels, whereby said star wheels are actuated simultaneously, and means for stopping said reels, successively, comprising brakes, one for each reel, and a brake actuating arm positioned to move with said link to actuate said brakes successively during the return movement of said link.
8. In a machine of the character described, a plurality of reels, means for actuating them, including a shaft, a handle for rotating said shaft, two discs on said shaft, one fixed to the shaft and the other free upon it, a reel-actuating link in contact with both discs, means for causing said discs to move together to carry said link, and cam means for moving said link out of contact with said discs to free it for return movement.
9. In a machine of the character described, a plurality of reels, means for actuating them, including a shaft, a handle for rotating said shaft, two discs on said shaft, one fixed to the shaft and the other free upon it, a reel-actuating link in contact with both discs, means for causing said discs to move together to carry said link, and cam means for moving said link out of contact with said discs to free it for return movement, and means for preventing return movement of one of said discs until said link is cammed out of contact with said disc.
10. In combination in a machine including a carriage, a plurality of reels positioned side by side, a movable mounted carriage, means for setting said reels in motion simultaneously and for stopping them successively, means for moving said carriage, a plurality of positioning wheels associated one with each of said reels, means for returning said carriage, a member carried by said carriage adapted to contact said positioning wheels, perforations and guiding cams formed in said wheels intermediate said perforations, said member adapted to be thrust through the perforation of one or more wheels when the latter are stopped with their perforations in line with said member, the return movement of said carriage being determined by the position assumed by said wheels upon being stopped, and aligning means for said positioning wheels whereby they are automatically properly positioned when stationary.
11. In combination in a machine including a carriage, a plurality of reels positioned side by side, a movable mounted carriage, means for setting said reels in motion simultaneously and for stopping them successively, means for moving said carriage, a plurality of positioning wheels associated one with each of said reels, means for returning said carriage, a member carried by said carriage adapted to contact said positioning wheels, perforations and guiding cams formed in said wheels intermediate said perforations, said member adapted to be thrust through the perforation of one or more wheels when the latter are stopped with their perforations in line with said member, the return movement of said carriage being determined by the position assumed by said wheels upon being stopped, and a brake in combination with said carriage moving means and effective to delay its return movement.

WILLIAM G. PETERS.
